UNITED STATES PATENT OFFICE.

ALBERT PICK, OF CHICAGO, ILLINOIS.

DESIGN FOR A GOBLET.

No. 37,917.

Specification for Design.

Patented March 27, 1906.

Application filed January 15, 1906. Serial No. 296,226. Term of patent 7 years.

To all whom it may concern:

Be it known that I, ALBERT PICK, a citizen of the United States, residing at Chicago, in the county of Cook and State of Illinois, have invented a new, original, and ornamental Design for a Goblet.

The accompanying drawing illustrates a design in accordance with my invention.

I claim—

The ornamental design for a goblet, as shown.

ALBERT $\frac{1}{2}$ PICK.
